HONING MECHANISM

Alfred Weiland, South Charleston, W. Va., assignor to General Machinery Ordnance Corporation, South Charleston, W. Va., a corporation of Ohio

Application May 26, 1942, Serial No. 444,591

19 Claims. (CL 51—184.1)

The present invention relates to gun barrels and more particularly to the finishing of the rifling grooves and the bores of the gun barrels or any other internally finished cylinder.

In the honing of gun barrels as heretofore practised, attempts have been made to expand the abrasive stones during the honing process but without practical success. It has been found that difficulties in manufacturing expanding devices preclude the required accuracy to get even pressure on all of the stones, which coupled with the difficulty of maintaining even pressure due to the uneven wear of the stones, has up to the present failed to satisfactorily solve the problem of efficient and accurate honing.

Some of the objects of the present invention are to provide an improved honing mechanism for gun barrels; to provide a honing mechanism wherein provision is made for accurate honing of the rifling grooves of a gun barrel; to provide a honing mechanism wherein provision is made for accurate honing of cylindrical bores of gun barrels; to provide a mechanism for expanding the honing stones of a honing mechanism for gun barrels; to provide a mechanism including movable honing stones in association with an expanding means whereby uniform pressure is maintained against all of the honing stones; to provide means for maintaining a uniform pressure upon a plurality of honing stones regardless of uneven wear of the stones in use; and to provide other improvements as will hereinafter appear.

In the accompanying drawings, Fig. 1 represents a longitudinal section of a rifle honing head embodying one form of the present invention; Fig. 2 represents a side elevation of a plurality of honing heads of the present invention on a smaller scale as assembled for use in a tandem arrangement; Fig. 3 represents a section on line 3—3 of Fig. 2; Fig. 4 represents a fragmentary transverse section showing a honing head operatively located in the corresponding rifling of a gun barrel; Fig. 5 represents a longitudinal section of a honing head as associated with a gun barrel having a cylindrical bore; and Fig. 6 represents a fragmentary section on line 6—6 of Fig. 5.

Referring to the drawings one form of the present invention consists of a plurality of abrasive stones or hones 13, each of generally rectangular shape and of a width to snugly fit and enter the rifling grooves 11 of a gun barrel 12. As shown these hones 13 are radially mounted respectively for sliding movement in through

slots 13 formed in a tubular body 14, the said slots 13 being substantially parallel to each other but angularly disposed with respect to the axis of the body 14.

5. For controlling the radial movement of the hones 13, a cylinder 15 of resilient material, such as rubber, fills the interior of the body 14 and abuts the inner faces respectively of the hones 13. It should be noted that the width of the hones 13, radially considered, is greater than the wall of the body 14, so that the required outward expansion of the hones can take place to perform the required honing of the gun grooves 11.

In order to cause the rubber cylinder 15 to be expanded to cause a uniform outward movement of the hones 13 under a uniform pressure, a metal cone 16 is pressed into contact with one end of the rubber cylinder 15 by means of a round nosed feed screw 17, which is threaded through an end plate 18. Bolts 20 securely fasten the plate 18 over one end of the body 20, while a like plate 21 is fastened by bolts 22 to the opposite end of the body 20. The plate 21 is provided with an opening 23, coaxially located with respect to the cylinder 15, and which serves to permit an anvil or abutment 24 to enter the body 20 and take a position between the rubber cylinder 15 and the plate 21, such anvil 24 having a width greater than the diameter of the opening 23. As shown, the face 25 of the anvil 24, which is towards the end of the cylinder 15, is a plane, preferably a circular one, having a diameter greater than that of the opening 23 and sufficiently large to expose an appreciable area to resist endwise expansion of the cylinder 15 under the pressure of the cone 16. The rear face 26 of the anvil 24 is a segment of a sphere which seats against the inner margin of the plate 21 which frames the opening 23. A stem 27 is attached to, and mounts, the anvil 23, such stem 27 being of less diameter than the opening 23 through which it passes for connection of another honing head where a tandem arrangement is desired. The clearance about the stem 27 permits the curved face of the anvil 24 to be self adjusting to compensate for axial distortion, if any.

In Fig. 1 the dotted lines adjacent the cone 16 and adjusting screw 17 indicate a step in bringing about compression of the cylinder 15. The screw 17 is provided with suitable flats 28 for engagement by a wrench or other suitable implement.

While a single honing head can be reciprocated through a gun barrel with excellent results, it is contemplated to employ a plurality

arranged in tandem so that all barrel grooves can be simultaneously honed. For example, each honing head may have fifteen expandable stones while the gun barrel may have forty-five rifling grooves and therefore, three heads are assembled one behind the other as shown in Fig. 2. The heads are successively interconnected by flexible or universal joints 30, which transmit the proper linear reciprocation while permitting torsional compensation where required. The stones for the respective heads are designated respectively by reference numerals 10, 21 and 32, and it should be noted that axially considered, the three sets of stones are out of alignment by an amount equal to the spacing of the rifling grooves 11. Thus, as will be seen from Fig. 3, each consecutive three grooves 11 will receive a stone 10, a stone 31, and a stone 32, and such relation will maintain throughout the circumference of the gun barrel. As a result, all of the rifling grooves 11 receive a simultaneous honing. A suitable connection 33 is provided for the protruding stem of the end head in order to attach the power transmitting means. While the head with its abrasive stones or stones is not only of value in the manufacture of gun barrels, it is also of great value in reconditioning gun barrels after use, in which case the honing head can be pulled through the gun barrel by a rope or other means.

In the form of the invention shown in Figs. 5 and 6, a honing head, such as shown in Fig. 1, is employed for honing the cylindrical bore of a gun barrel. In this instance, the expansion of the resilient cylinder 15 uniformly projects the stones 10 in the required manner but the head, instead of being reciprocated, is attached to a rotating power means which rotates the head as it traverses the gun barrel. Any suitable means for causing the head to rotate in the cylinder 33 can be used and is attached to a rod 34 which is formed as an extension of the feed screw 17. During such rotary action the screw 17 is fixed against turning relative to the head or body 14 by lock nuts 35. Where long cylinders are to be honed it has been found advantageous to mount the cylinder on rollers which travel on a track, so that in this way the stroke of the head can be compensated and no change of stroke is necessary.

While in the foregoing specific reference has been made to the honing of gun barrels and the rifling thereof, the invention is not limited to such use as it can also be applied effectively to the honing of motor cylinders or any other cylinders requiring internal finishing.

Having thus described my invention, I claim:

1. A reciprocable honing mechanism consisting of a head to enter the bore of a gun barrel, abrasive stones mounted for movement relative to said head and arranged to be projected beyond the periphery of said head, and means including a solid resilient deformable body confined against deformation except in the direction of said stones for projecting said stones outwardly into contact with the interior of said gun barrel.

2. A reciprocable honing mechanism for the rifling grooves of a gun barrel, consisting of a head to enter the bore of a gun barrel, a plurality of abrasive stones dimensioned to respectively interfit with the rifling grooves of a gun barrel, said stones being movably mounted in said head to project circumferentially of said head, and expanding means simultaneously act-

ing on all of said stones to project the same outwardly into said grooves, said means including a solid resilient deformable body confined by said head and stones.

3. A reciprocable honing mechanism for the rifling grooves of a gun barrel, consisting of a tubular cylindrical head having a plurality of slots circumferentially arranged therethrough, a plurality of abrasive stones respectively mounted for sliding movement in said slots, plates closing the respective ends of said head to form an enclosed chamber, a body of resilient material in and substantially filling said chamber, and means to compress said body to cause it to expand laterally and uniformly project said stones outwardly.

4. A reciprocable honing mechanism for the rifling grooves of a gun barrel, consisting of a tubular cylindrical head having a plurality of slots circumferentially arranged therethrough in parallel relation and angular with respect to the axis of said head, a plurality of abrasive stones respectively mounted for sliding movement in said slots, a body of resilient material confined within said head and contacting said stones, a device for compressing said body to cause it to expand uniformly against said stones to project the latter outwardly into the rifling grooves of a gun barrel.

5. A reciprocable honing mechanism for the rifling grooves of a gun barrel, consisting of a tubular cylindrical head having a plurality of slots circumferentially arranged therein in parallel relation and angular with respect to the axis of said head, a plurality of abrasive stones respectively mounted for sliding movement in said slots, a body of resilient material inside of said head, and means including a metal cone for causing said body to expand uniformly against said stones to project the latter outwardly into the rifling grooves of a gun barrel.

6. A reciprocable honing mechanism for gun barrels consisting of a head to enter the bore of a gun barrel, said head having a chamber and slots forming communication between said chamber and the outside of said head, abrasive stones mounted respectively in said slots for movement relative to said head and arranged to be projected beyond the periphery of said head, an anvil at one end of said chamber, a body of resilient deformable material confined by said chamber in contact with said stones and said anvil, and means at the opposite end of said chamber for compressing said body against said anvil to cause outward expansion of said stones.

7. A reciprocable honing mechanism for gun barrels consisting of a head to enter the bore of a gun barrel, said head having a chamber and slots forming communication between said chamber and the outside of said head, abrasive stones mounted respectively in said slots for movement relative to said head and arranged to be projected beyond the periphery of said head, an anvil at one end of said chamber, means mounting said anvil for axial self-adjustment, a solid body of resilient material in said chamber in contact with said stones and said anvil, and means at the opposite end of said chamber for compressing said body against said anvil to cause outward expansion of said stones.

8. A reciprocable honing mechanism for gun barrels consisting of a head to enter the bore of a gun barrel, said head having a chamber and a slot forming communication between said chamber and the outside of said head, an abrasive

stone movably mounted in said slot and arranged to be projected beyond the periphery of said head, and means including a solid deformable resilient body confined against deformation except in the direction of said stones for causing said stone to be uniformly pressed outwardly to honing position.

9. A reciprocable honing mechanism for the rifling grooves of a gun barrel, consisting of a plurality of heads, each head comprising a closed end cylinder having circumferentially arranged slots spaced to correspond respectively to the spacing of certain rifling grooves of a gun barrel, the sum of the slots of all of said heads being equal to the number of rifling grooves, abrasive stones slidably mounted in the respective slots and arranged to project beyond the periphery of

said cylinder, means including a solid resilient deformable body confined by each head and stone for projecting said stones to honing position, and means to connect said heads in tandem relation with each set of stones alined with a different set of grooves, whereby all of said grooves are simultaneously honed by said heads.

10. A mechanism for honing the bore of a cylinder consisting of a head, abrasive stones projecting beyond the interior and exterior peripheries respectively of said head and movable with respect thereto, and means including a solid deformable resilient member confined by said head and stones for simultaneously expanding said stones to uniformly project said stones into honing relation with a cylinder.

ALFRED WEILAND.
